UNITED STATES PATENT OFFICE.

FRANK GILBERT HINSDALE, OF NEW YORK, N. Y.

PILING MACHINE.

Original application filed January 12, 1923, Serial No. 612,176. Divided and this application filed October 29, 1925. Serial No. 65,540.

My invention relates to machines for throwing and piling fabrics such as for instance lace curtains, and has for its object to provide a novel and simple machine for 5 automatically piling fabrics in predetermined lots and more particularly for piling lace curtains in kier lots for transference to the kier in the process of producing lace curtains. Other objects of the invention 10 will appear from the description hereinafter and the features of novelty will be pointed out in the claims. The present application is a division of another application filed by me in the United States Patent Office on January 12, 1923, Serial No. 612,176.

Reference is to be had to the accompanying drawings, which illustrate an example of the invention without defining its limits, 20 and in which Figure 1 is a diagrammatic view illustrating the novel machine in use for piling curtains; Figure 2 is a front view partly in section of the machine, and Figure 3 is a side view thereof partly in section.

As shown in the drawings, the machine, which may be termed a rapid piler, comprises a frame 10 preferably suspended by means of rollers 11 from a track 12 and 30 provided at its lower portion with a guide roller 13 arranged to engage and travel along a rail 14 to maintain the frame 10 against vibration and in its intended path. A drum 15 is carried by a shaft 16 journaled in suitable bearings 17 secured at the proper places upon the frame 10; the shaft 16 carries also pulley 18 which is connected by means of a belt 19 with a pulley 20 secured upon the shaft of an electric motor 21 mounted upon the frame 10, as shown in Figure 2. A pressure roll 22 is located in surface engagement with the drum 16 and is carried by a shaft 23 journaled in bearing blocks 24 slidably mounted in guides 25 forming part of or secured to the frame 10; for the purpose of maintaining the pressure roll 22 under pressure towards the drum 15, springs 26 are provided which preferably surround stems 27 connected 40 with the bearing blocks 24 and slidably in guides 28, as shown in Figure 3. In the preferred construction the surfaces of the drum 15 and pressure roll 22 are covered with a hard wool felt of suitable thickness 45 or are otherwise treated to cause the drum

and the roll to develop a frictional surface grip of maximum extent.

The machine further includes a deflector 29 supported upon arms 30 carried by a shaft 31 which is journaled in bearings 32 60 fixed upon the frame 10; the shaft 31 is so located and the associated parts are so arranged and proportioned that the deflector 29 is movable in a circular arc from a position tangent to the drum 15 and inclining 65 downwardly to an upwardly inclined position and back again. Any suitable means may be provided for pivotally reciprocating said deflector in a gradual and continuous manner; for instance, the mechanism illustrated in Figure 3 may be utilized for this purpose. This mechanism comprises a suitable cam 33 mounted upon a shaft 34 journaled in bearings 35 located upon the frame 10, said shaft 34 further carrying a 70 worm gear 36 which meshes with a worm pinion 37 fixed upon a countershaft 38; the latter is rotatably mounted by means of bearings 39 upon the frame 10 and is provided with a bevel gear 40 meshing with 75 a bevel gear 41 located upon the drum shaft 16 whereby said worm gearing and cam are operated. A roller 42 arranged to engage the cam 33 is mounted upon a cam-follower arm 43 depending from a shaft 44 80 journaled in bearings 45 upon the frame 10 and having its free end connected by means of a strap 46 with one of the arms 30, as shown in Figure 3. The roller 42 is maintained in operative engagement with 85 said cam 33 by means of a spring 47 which has its one end attached to a convenient portion of the frame 10 and its other end connected by means of a strap 48 with the other arm 30. An operating lever 49 is 90 fixed upon the shaft 44 and is provided at its free end with a cord 50 which depends therefrom within easy reach of the attendant. At a point in registry with the drum 16 and roll 22, the machine is provided with 95 a pot-eye 51 which is supported upon the frame 10 by a bracket 52 for guiding the lace to said drum, as will appear more fully hereinafter.

In practice, this machine is operated by 100 the motor 21, which transmits motion through the medium of the pulleys 20 and 18 and belt 19 to the drum 15, which, in turn, because of its surface engagement therewith, imparts motion to the pressure 110

roll 22. At the same time, as the drum shaft 16 is actuated by the motor 21 it will, through the medium of the bevel gears 40 and 41, operate the countershaft 38 and 5 worm gearing 37, 36 which, in turn, brings about a rotation of the cam 33. This causes the follower arm 43 to be pivotally swung, for instance, from the position shown in Figure 3 whereby a pull is exerted upon 10 the strap 46; this results in rocking the deflector shaft 31 and moves the deflector 29 in a circular path toward the drum 15, the spring 47 being, by this operation, stretched under tension. As the cam 33 continues 15 to operate, the follower arm 43 will finally describe a swinging movement in the reverse direction, because of the shape of said cam 33, whereby the deflector 29, by the action 20 of the spring 47 upon the strap 48 and arm 30, will be caused to move in a circular path away from the drum 15. The gradual pivotal reciprocation of the deflector 29 toward and away from the drum 15 in the manner described, is repeated 25 throughout a given period of operation; if, at any time, a more rapid operation of the deflector 29 in a direction away from the drum 15 is temporarily desired, this may be accomplished by exerting a downward pull 30 upon the cord 50 to pivotally actuate the lever 49 and thereby swing the follower arm 43 independently of the cam 33. In utilizing this machine, for instance, in piling kier lots in the manufacture of lace curtains, a roll of lace *a* is rotatably supported 35 by means of a split-bar *b* upon a suitable roll stand *c* and the end of the lace is passed preferably in twisted form through the pot-eye 51 into the nip between the 40 pressure roll 22 and drum 15 which, in operation, is driven at a high rate of speed, for instance two hundred and fifty yards per minute. The lace accordingly passes through this nip at a very rapid rate and 45 assisted by the frictional surface grip exerted by the drum 15 and roll 22 is shot forward from said drum, or in other words is trajectory from the machine in a trajectory which carries it a distance of twelve 50 or more feet, in front of said machine assuming the deflector 29 to be in the highest position of inclination illustrated in Fig. 3. As the deflector gradually moves downwardly, the trajectory described by the lace and 55 the distance it is thrown from the drum 15 is gradually and continuously reduced until the lace is finally trajectory forward a minimum distance to a point perhaps two feet in front of the machine. In this way, and 60 by this means, the deflector, during its pivotal reciprocation, gradually and progressively varies the trajectory described by the lace as it is trajectory from the machine so that the lace is folded back and forth, as it 65 were, into the form of the pile *d*. The ma-

chine is roller mounted upon the track 12 and rail 14 in order to enable it to be readily shifted to different locations for piling material thereat or for making a plurality of individual piles at a given point. From 70 the pile *d* the lace is transferred into a conventional kier in any convenient manner.

While the machine is primarily adapted for piling lace curtains in predetermined or kier lots, it may be utilized in many other 75 connections with equal efficiency.

Various modifications in the sequence of the various steps of the method set forth and in the steps themselves and various changes in the mechanism shown and described may be made within the scope of the claims without departing from the nature of my invention.

I claim:

1. A machine for piling material in predetermined lots comprising means for forcibly casting the material outwardly from the machine to cause said material to describe a trajectory, and means for varying the curve of said trajectory from a given maximum to a minimum and vice versa to thereby pile the material in folds. 85

2. A machine for piling material in predetermined lots comprising means for forcibly casting the material outwardly from the machine to cause said material to describe a trajectory, a deflector for determining the curve of said trajectory, and means for reciprocating said deflector to vary said curve of said trajectory from a given maximum to a minimum and vice versa to thereby pile the material in folds. 90

3. A machine for piling fabric in predetermined lots comprising cooperating rolls at least one of which is driven at high speed to forcibly cast the fabric horizontally outward from the machine to cause said fabric to describe a trajectory, means for guiding the fabric to said rolls, and means for progressively varying the curve of said trajectory from a given maximum to a minimum and vice versa to thereby pile the fabric in folds. 105

4. A machine for piling fabric in predetermined lots comprising cooperating rolls, means for positively driving at least one of said rolls at a speed sufficiently high to forcibly cast the fabric horizontally outward from the machine to cause said fabric to describe a trajectory, a pot-eye for guiding said fabric to said rolls, and means for progressively varying the curve of said trajectory from a given maximum to a minimum and vice versa to thereby pile the fabric in folds. 115

5. A machine for piling fabric in predetermined lots comprising cooperating rolls at least one of which is driven at high speed to forcibly cast the fabric horizontally outward from the machine to cause said fab- 120

130

ric to describe a trajectory, a pivoted deflector for determining the curve of said trajectory, a cam for pivotally reciprocating said deflector to progressively vary the curve 5 of said trajectory from a given maximum to a minimum and vice versa to thereby pile the fabric in folds, and means for operating said cam.

6. A machine for piling webs of fabric in 10 predetermined lots comprising a support, a drum rotatably mounted thereon, a pressure roll in operative relation to said drum, means on said support for rotating the drum at a speed sufficiently high to forcibly cast 15 the fabric horizontally outward from the machine to cause said fabric to describe a trajectory, a pivoted deflector for determining the curve of said trajectory and mechanism operatively connected with said drum 20 for pivotally reciprocating said deflector to vary the curve of said trajectory from a given maximum to a minimum to thereby pile the fabric in folds.

7. A machine for piling webs of fabric in 25 predetermined lots comprising a support, a drum rotatably mounted thereon, a pressure roll contiguous to said drum, a motor carried by said support for operating said drum to traject the fabric from said machine, a deflector for determining the trajectory of projection, a follower arm connected with said deflector, a cam for mechanically operating said arm to pivotally reciprocate said de-

flector whereby said trajectory is progressively varied to pile the fabric in folds, 35 mechanism for operating said cam, and means for manually operating said arm to actuate said deflector.

8. A machine for piling webs of fabric in predetermined lots comprising a traveling 40 support, means carried thereby for trajecting the fabric from said machine, a motor located upon said support for operating said means, and means on said support for progressively varying the trajectory whereby 45 said fabric is piled in folds.

9. A machine for piling webs of fabric in predetermined lots comprising a traveling carriage, a drum rotatably mounted thereon, a pressure roll contiguous to said drum, a 50 pot-eye on said support for guiding the fabric to the nip between said drum and roll, a motor located upon said carriage for operating said drum to traject the fabric from said machine, a deflector pivotally mounted 55 upon said carriage for determining the trajectory of projection, a follower arm connected with said deflector, a cam for operating said arm to pivotally reciprocate said deflector whereby said trajectory is progressively varied to pile the fabric in folds, and mechanism connected with said drum for operating said cam.

In testimony whereof I have hereunto set my hand.

FRANK GILBERT HINSDALE.
